UNITED STATES PATENT OFFICE.

LEE DE FOREST AND CHARLES LOGWOOD, OF NEW YORK, N. Y., ASSIGNORS TO RADIO TELEPHONE & TELEGRAPH COMPANY, A CORPORATION OF DELAWARE.

WIRELESS RECEIVING SYSTEM.

1,170,881.

Specification of Letters Patent.

Patented Feb. 8, 1916.

Application filed March 12, 1914. Serial No. 824,171.

To all whom it may concern:

Be it known that we, LEE DE FOREST and CHARLES Logwood, citizens of the United States, residing at New York, in the county of Bronx, State of New York, have made a certain new and useful Invention in Wireless Receiving Systems, of which the following is a specification.

This invention relates to wireless receiving systems.

The object of the invention is to provide a receiving system for wireless communication wherein the sensitiveness of an audion is utilized as a detector of alternating or pulsating electric currents, whether of high or low frequency, and also as a relay or amplifying device for such currents.

A further object of the invention is to provide circuit arrangements whereby the audion detector and amplifier is rendered selective as to certain impulses which it is desired to detect or amplify, to the exclusion of other impulses differing in frequency or wave form from those which it is desired to receive or amplify.

Other objects of the invention will appear more fully hereinafter.

The invention consists substantially in the circuit arrangement and relation of parts and interdependent action hereinafter more fully set forth, as illustrated in the accompanying drawings and finally pointed out in the appended claims.

Referring to the accompanying drawings,—Figure 1 is a circuit diagram showing one arrangement of circuits adapted to carry out the principles of my invention. Fig. 2 is a similar view showing a plurality of audion grids and plates. Fig. 3 is a view similar to Fig. 2, showing a transformer associated in the circuits of the audion grids and plates. Fig. 4 is a view showing similar circuit arrangements in which the audion serves as a relay.

The same part is designated by the same reference character wherever it occurs throughout the several views.

In the drawings, and referring particularly to Fig. 1, N designates the antenna of a wireless receiving system, and E the ground or capacity connection therefor. Associated with the antenna in any suitable or any of the well known methods, is the usual oscillating circuit. An inductive asso-

ciation of the antenna and oscillating circuit is shown as one form capable of accomplishing the desired results. In this coupling, a transformer is employed, the primary P, of which, is in the antenna circuit, and the secondary S, in the oscillating circuit, a variable condenser C₁ being connected across the terminals thereof in the usual manner. This condenser serves to tune the secondary receiving circuit to the frequency of the impulses which it is desired to receive in the well understood manner.

The audion bulb U is provided with the usual filament F, conductor plate W, and intermediate conductor G, preferably in the form of a grid, wire or perforated plate. A battery A is included in the circuit of the filament F. Also included in the battery filament circuit is an adjustable resistance or rheostat indicated at R, by means of which the battery current may be controlled. A second battery B is employed, one terminal of which is connected to the plate W and the other terminal to one side of the circuit of filament F. The purpose of the B battery is to impress the required electro-motive-force between the filament F and the plate W, and, to this end, one of the terminals of said battery B is made adjustable, as shown.

The terminals of the oscillating circuit are, respectively, in the grid and plate elements of the bulb. The circuit connection of that portion of the oscillating circuit which terminates in the grid, may, if desired, contain a condenser C₂.

The circuit of battery B and plate W, contains a suitable signal indicating device, such, for instance, as a telephone receiver T. The circuit which contains the secondary S and terminates in the grid G and plate W, respectively, is of course a circuit in which high frequency oscillations are created. It may sometimes be desired to prevent and insure against these high frequency oscillations entering the circuit of the battery B. To accomplish this we place a choke coil K in the circuit connection of the plate W with the battery B, and between the plate W and the battery B outside of the terminal connection of coil K with the plate W. While the choke coil K may be dispensed with, we prefer to employ it for the purpose stated.

In Fig. 2, we have shown an arrangement employing two grids G₁, G₂ and two plates

W₁, W₂ in the audion bulb U, and we connect one terminal of the circuit of secondary coil S with both grids G₁ G₂, and the other terminal of said coil S with plate W₁. In this arrangement one terminal of battery B is connected to one side of the circuit of filament F, while the other terminal of said battery B contains the signal indicating device T, and is connected to the other plate W₂.

In Fig. 3, an audion bulb U is employed which contains two grids G₁ G₂, and two plates W₁, W₂ as in the case of Fig. 2, but a transformer having the coils L₁ L₂, are employed, the coil L₁ being shunted by the variable condenser C₂ and being connected to both audion grids G₁ G₂. The secondary coil L₂, is included in the circuit connection of battery B, which also includes the signal indicating device T, and this circuit connection also includes both the audion plates W₁ W₂. The other terminal of the battery B is connected to one side of the circuit of filament F. With this arrangement it will be observed that the grids G₁ G₂ are connected in parallel to each other, and the plates W₁ W₂ are likewise connected together in parallel. This we have found to be a preferable arrangement as it gives greater conducting surfaces or, so to speak, larger areas of ionic targets, which greatly increases the sensitiveness of the device, particularly when employed for amplifying the received oscillations. If desired and in order to make more critical the action of the device and to increase its sensitiveness, a permanent magnet, preferably of the horseshoe form as indicated at M, may be employed and so placed as to exert its influence upon the elements of the audion bulb.

In Fig. 4 we have shown an arrangement in which the audion acts to amplify high frequency oscillations as such and without transforming the same from high to low frequency as is ordinarily the case with radio detectors. In this case L₃ L₄ are respectively, the primary and secondary windings of a high frequency transformer, and is constructed without an iron core. In this connection we note that the transformer L₁ L₂ of Fig. 3 is designed for low or "audio" frequencies and preferably contains an iron core as indicated. In the case of Fig. 4, the primary L₃ is contained in the circuit connection of the battery B to the audion plate W, while the coil L₄ is contained in a circuit D which serves as an outlet circuit for the transformed and amplified high frequency currents. In this arrangement the oscillating circuit which contains the secondary coil S is connected between the grid G and plate W, as shown. The impressed voltage of battery B and the current of battery A are so relatively adjusted, in practice, that the circuit which connects the grid and plate elements of the detector has a tendency

to oscillate at a certain definite frequency with a given bulb. This frequency depends to a great extent upon the magnitude of the potential impressed across the space between the plate W and the filament F, and also upon the temperature of the filament. In other words this oscillating circuit does not in any way follow the Thompson law. If the potential in the circuit of battery B and the current in the circuit of filament F, are so relatively adjusted that the grid circuit is just ready to be set into oscillation, we find that said circuit is highly responsive to received impulses the group frequency of which is that at which the circuit tends to oscillate, but not sensitive to group frequencies materially differing from the natural period of the grid circuit.

In the circuit arrangement shown in Fig. 1, the audion itself is selective to the received high frequency oscillations to an extraordinary degree. In this case the audion is the source of high frequency oscillating currents, the energy of which is controlled by the batteries A and B, and the frequency of which is determined by the amount of inductance in the coil S, and its associated coil P, and by the adjustment of condensers C₁ C₂. If the received impulses be from an undamped continuously oscillating source, beats are set up in the audion circuit due to interference between the received impulses and those generated in the audion circuit, and if these two frequencies are so relatively adjusted as to be sufficiently near each other this "beat note" can be heard in the signal device or telephone receiver as a high distinctive and distinguishable note, the pitch of which can be regulated by varying the capacity of condensers C₁ and C₂ or the inductance S. Similarly, as the natural rate of oscillations of the audion and of the oscillating circuit connected across its cold grid and plate elements, depend to some extent on the voltage of the battery B, and the temperature of the filament F, the pitch of the beat note referred to can be regulated to a certain extent by adjusting or varying the voltage of battery B or the current in the circuit of filament F.

In de Forest Patent No. 995,126, granted June 13, 1911, is shown an audion amplifier or detector energized from a local source of high frequency current having a frequency higher than the more essential frequencies accompanying sound waves, and which audion as shown is so arranged with reference to the circuit of the local source and to the antenna circuit, that if the frequencies of the distant and local sources are nearly the same, beat notes will be heard in the telephone receiver associated with the audion detector. In the present arrangement, however, while the action is similar the audion itself sets up the continuous oscillation

tions. Where the received impulses are slowly damped, that is, where they originate from a transmitting station employing for example, a quenched spark apparatus, the 5 audion and circuit arrangement hereinabove set forth becomes highly selective to said impulses, by adjusting the audion circuits so that there is set up therein a continuous oscillation the frequency of which coincides, 10 or nearly coincides with that of the impulses which it is desired to receive.

In the arrangement shown in Fig. 3 the audion becomes a source of continuous high frequency impulses for the circuit of secondary S, and also a source of low frequency impulses in the circuit of the telephone receiver. The latter are rendered very weak or eliminated entirely by the adjustments referred to, of the impressed voltage of the circuit of battery B, and the current of battery A in the filament circuit, until impulses are received having a spark or group frequency coinciding with that of the telephone-audion circuit. In this manner the audion and its associated circuits become doubly selective.

In the arrangement shown in Fig. 4, the audion becomes an amplifier for high frequency currents as such. The oscillating 30 circuit is shown connected between the grid and the plate. The amplified current circuit is that circuit which is connected at one terminal to the plate W and at the other terminal to one side of the filament. The 35 condenser C₂, in this arrangement, may, if desired, be dispensed with, and the condenser C₃ may be merely a "blocking" condenser of large capacity instead of a small variable condenser.

40 It is to be observed that in all cases, except that shown in Fig. 2, the positive side of battery B is connected to the audion plate W, (Figs. 1 and 4) or to the plates W₁ W₂ (Fig. 3). In Fig. 2, the positive side of battery B is connected to one side of filament F, and the other side of said battery is connected to plate W₂.

In practice we prefer to insert an impedance coil L₅ in the circuit of battery B, 50 said coil having a resistance of several thousand ohms and containing an iron core, as indicated in the drawing. The amplified high frequency currents are transformed by means of the air core high frequency transformer L₃ L₄, at any desired ratio of voltage, and led off at the secondary terminals D.

While we have shown various circuit arrangements embodying the broad principles of our invention we wish it to be understood that other arrangements besides those specifically shown and described may be employed for accomplishing the same or similar results without departing from the 60 spirit and scope of our invention. We do

not desire to limit ourselves, therefore, in the broadest scope of our invention to specific circuit arrangements shown. But

What we claim as new and useful and of our own invention, and desire to secure by Letters Patent is,—

1. In a wireless apparatus, an audion having a grid element and a wing or plate element, and a series oscillating circuit having one terminal associated with the grid element and the other terminal associated with the wing or plate element. 75

2. The combination with an audion having a grid and a wing element, of a series oscillating circuit having its terminals respectively connected to said grid and wing elements. 80

3. In a wireless receiving system, a sensitive detector including cold electrodes and a hot electrode, and a plurality of inductively related circuits associated therewith, one of said circuits being a series circuit and connected at its terminals with said respective cold electrodes. 85

4. In a wireless receiving system, a detector including cold electrodes and a hot electrode, and a series oscillating circuit connected at its terminals to said cold electrodes respectively. 90

5. In a wireless receiving system, a detector including cold electrodes and a hot electrode, and a plurality of inductively related circuits associated therewith, one of said circuits being a series oscillating circuit and having its terminals respectively connected to the cold electrodes. 95

6. In a wireless receiving system, a sensitive gas detector including cold electrodes and a hot electrode, a plurality of inductively related circuits associated with said electrodes, one of said circuits being a series circuit and having its terminals respectively connected to the cold electrodes, and means to generate electrical oscillations in said series circuit. 105

7. In a wireless receiving system, a detector including a filament, a plate, and a grid, means for supplying current to the filament, and a series oscillating circuit connected to the grid and to the plate. 110

8. In a wireless receiving system, an audion having cold electrodes and a hot electrode, a series oscillating, a current supply and a voltage supply circuit associated therewith, the terminals of the oscillating circuit being respectively connected to the cold electrodes, and means to produce oscillations in said last mentioned circuit. 120

9. In a wireless receiving system, an audion having cold electrodes and a hot electrode, a series oscillating, a current and a voltage supply circuit associated with said audion, said oscillating circuit having its terminals respectively connected to the cold electrodes, and said voltage supply circuit 125

130

having one terminal connected to a cold electrode and the other to the hot electrode.

10. In a wireless receiving system, an audion having cold electrodes and a hot electrode, a series oscillating, a current supply and a voltage supply circuit associated with said audion, said oscillating circuit having its terminals respectively connected to the cold electrodes, and said voltage supply circuit being inductively related to the oscillating circuit and having one terminal connected to a cold electrode and the other to the hot electrode.

11. In a wireless receiving system, an audion having cold electrodes and a hot electrode, a series oscillating circuit having its terminals respectively connected to the cold electrodes, a current supply circuit connected to the hot electrode, and a voltage supply circuit having one terminal connected to a cold electrode and the other to the hot electrode.

12. In a wireless receiving system, an audion having cold electrodes and a hot electrode, a series oscillating circuit having its terminals respectively connected to the cold electrodes, a current supply circuit connected to the hot electrode, a voltage supply circuit having one terminal connected to a cold electrode and the other to the hot electrode, and means to vary the voltage in said voltage supply circuit.

13. In a wireless receiving system, an audion having cold electrodes and a hot electrode, a series oscillating circuit having its terminals respectively connected to the cold electrodes, a current supply circuit connected to the hot electrode, a voltage supply circuit having one terminal connected to a cold electrode and the other to the hot electrode, and means to vary the current in the current supply circuit.

14. In a wireless receiving system, an audion having cold electrodes and a hot electrode, a series oscillating circuit having its terminals respectively connected to the cold electrodes, a current supply circuit connected to the hot electrode, a voltage supply circuit having one terminal connected to a cold electrode and the other to the hot electrode, means to vary the voltage and current supplies.

15. In a wireless receiving system, an audion having cold electrodes and a hot electrode, a series oscillating circuit having its terminals respectively connected to the cold electrodes, a current supply circuit connected to the hot electrode, a voltage supply circuit having one terminal connected to a cold electrode and the other to the hot electrode, and means to vary the voltage in said voltage supply circuit, said oscillating circuit being inductively related to one of said supply circuits.

16. In a wireless receiving system, an au-

dion having cold electrodes and a hot electrode, a series oscillating circuit having its terminals respectively connected to the cold electrodes, a current supply circuit connected to the hot electrode, a voltage supply circuit having one terminal connected to a cold electrode and the other to the hot electrode, and means to vary the voltage in said voltage supply circuit, said oscillating circuit being inductively related to said voltage supply circuit.

17. In a wireless receiving system, an audion having cold electrodes and a hot electrode, a series oscillating circuit having its terminals respectively connected to the cold electrodes, a current supply circuit connected to the hot electrode, a voltage supply circuit having one terminal connected to a cold electrode and the other to the hot electrode, and means to vary the voltage in said voltage supply circuit and a transformer coupling between the oscillating and one of said supply circuits.

18. In a wireless receiving system, an audion having cold electrodes and a hot electrode, a series oscillating circuit having its terminals respectively connected to the cold electrodes, a current supply circuit connected to the hot electrode, a voltage supply circuit having one terminal connected to a cold electrode and the other to the hot electrode, and means to vary the voltage in said voltage supply circuit and a transformer coupling between the oscillating and voltage supply circuits.

19. In a wireless receiving system, an audion having a filament, a plurality of grids and a plurality of plates, a current supply circuit connected to the filament, a voltage supply circuit connected to the plates and an oscillation circuit connected to the grids.

20. In a wireless receiving system, an audion having a filament, a plurality of grids and a plurality of plates, a current supply circuit connected to the filament, a voltage supply circuit connected to the plates, and an oscillation circuit connected to the grids, said circuits being interlinked with each other.

21. In a wireless receiving system, an audion having a filament, a plurality of grids and a plurality of plates, a current supply circuit connected to the filament, a voltage supply circuit connected to the plates, and an oscillation circuit connected to the grids, said oscillation and voltage supply circuits being inductively related to each other.

22. In a wireless receiving system, an antenna circuit, a series oscillating circuit associated therewith, an audion having cold electrodes and a hot electrode, said series oscillating circuit having its terminals respectively connected to said cold electrodes.

23. In a wireless receiving system, an antenna circuit, a series oscillating circuit as-

sociated therewith, an audion having cold electrodes and a hot electrode, said series oscillating circuit having its terminals respectively connected to said cold electrodes, 5 a signal device, a circuit therefor, the terminals of said signal circuit respectively connected to one of the cold electrodes and to the hot electrode, said oscillating circuit having one terminal connected to one of the 10 cold electrodes and the other terminal connected to the other cold electrode and be-

tween said last mentioned electrode and the signal device.

In testimony whereof we have hereunto set our hands in the presence of the sub- 15 scribing witnesses, on this 7th day of March A. D., 1914.

LEE DE FOREST.
CHARLES LOGWOOD.
